UNITED STATES PATENT OFFICE.

CARL J. PIHL, (NOW BY JUDICIAL CHANGE OF NAME CARL J. PIEL,) OF BOSTON,
MASSACHUSETTS.

THREAD-CUTTING DIE.

1,416,059.

Specification of Letters Patent. Patented May 16, 1922.

Application filed April 18, 1919, Serial No. 291,375. Renewed July 10, 1920. Serial No. 395,381.

To all whom it may concern:

Be it known that I, CARL J. PIHL, (now by judicial decree named CARL J. PIEL,) a citizen of the United States, and resident 5 of Boston, county of Suffolk, and Commonwealth of Massachusetts, have invented certain new and useful Improvements in Thread-Cutting Dies, of which the following is a full, clear, and exact specification.

10 The objects of this invention are to produce a die constructed in sections in such a manner that when in use the sections can be accurately positioned and maintained in such position by positively reliable holding 15 means which permits the ready disassembling of the die sections for the purpose of regrinding. A further object is to so form and construct the sections comprising the complete die that there will be provided 20 ample clearance beyond each cutting edge so as to avoid the dragging or rubbing of the internal edge of each section against the cylindrical surface of the work formed by the cutting edge.

25 For holding purposes I make the die in sections which are held together as a unit by a clip or encircled holder of novel construction which facilitates the positive alignment of the die sections with one another while holding them together as a unit 30 for handling when outside of the die stock.

Another feature of the invention consists in the peculiar form and construction due to a method of constructing the die sections 35 so that there will be provided ample clearance back of each cutting edge on the inside surface of the die.

These and other features of the invention will be particularly explained in this specification and will be defined in the claims hereto annexed.

In the accompanying drawings I have illustrated the preferred form of the invention together with certain modifications 45 thereof in which:

Figure 1 is a main assembled view showing the assembled die operatively held in the die stock.

Figure 2 is a detail view of the sectional 50 die assembled for insertion into the die stock.

Figure 3 is a detail view of a modified form of the holding clip.

Figure 4 is an assembled view of the die sections encircled by an annular holding 55 clip.

Figure 5 is a detached view of the preferred form of holding clip.

Figures 6, 7, and 8 show modified forms 60 of holding clip both separated and assembled characterized by a rectangular formation.

Figures 9 and 10 are enlarged views 65 showing the method of cutting and forming the sectional die.

I will first describe the method of constructing the die sections which form the die proper having reference to the four-part or quadrant die shown in the drawings although it will be understood that the 70 same principles are applicable to a die made of more or less sections.

In practice, according to the form shown, I take four quadrant shaped sections 1, 2, 3 and 4 and insert them in a holding ring 75 5 provided with four pairs of set screws 7 and 8 which are threaded radially so as to project inward through said holding ring. The screws are then adjusted so that the straight or radial edges of each quadrant 80 are positioned with one such edge extending beyond the center while the other edge is retracted the same distance away from the center. In this way all four quadrants are offset along both radial edges in relation to the center of the holding ring, such offset being a symmetrical by reason of the fact that one side edge is retracted from the center while the other side edge is advanced beyond it.

When all four sections have been thus securely offset in the holding ring a hole is centrally bored concentric with the center of the holding ring and the interior surface of said central hole is then tapped to form 95 the proper threads. After the boring and tapping operation four smaller holes corresponding to the number of the sections are bored symmetrically so as to intersect each pair of adjacent edges of the die and 100 the periphery of said central hole as shown in Figure 10. If preferred, however, the

boring of the small symmetrically arranged holes 11 may precede the threading or tapping of the central hole. When so bored and threaded the die sections are ready for assembly and use.

For such assemblage I prefer to employ a clip such as is shown in Figures 1, 2 and 5 which is a flat spring metal ring 13 having a right angle flange 20 extending inwardly from one side edge and having two inwardly projecting hooks at the ends of the ring.

By using this construction the four sections can be readily inserted from the open or unflanged side of the clip and forced down against the retaining flange or lip 20 with strong pressure so as to secure positive alignment in the same plane, the hooks 14 serving to securely grip and hold the sections against circumferential or other displacement without requiring the spring clip to be unduly sprung or expanded beyond its normal die-holding position in the effort to pass the hooks over the short radial gap between two of the die sections.

In Figure 3 I have shown a ring formed without the right angle flange or retaining lip and in Figure 4 I have shown the sections assembled with a clip having no retaining hooks. However, I prefer to use the hooks since they tend to position the die sections firmly against each other except where the gap is left at the open side of the clip. Moreover, the hooks receive the thrust of the expanding or anchoring screw 16 carried by the stock so that there is less likelihood of producing any offset laterally from the plane of the die than if the screw has direct engagement with the die sections themselves.

The ring 15 of the die stock is made so as to easily admit the die sections in assembled position and is provided with the main setting screw 16 and any suitable number of peripheral holding screws 17 for firmly securing the die within the stock.

The boring of the small holes 11 leaves each die with a cutting edge 19, the point of said cutting edge projecting very much farther inward toward the center of the die than the interior threaded portions of the die between the holes 11. Owing to the fact that the threaded surfaces of the dies are formed on circles that are offset laterally in two directions from the center of the assembled die, there is a sharp angle of divergence produced between the curve of the threads and the circle passing through the extreme cutting edges so as to afford ample sufficient clearance of the threaded surfaces of the die back of each cutting edge.

Obviously the die may be disassembled as often as may be needful for regrinding and can be reassembled to exactly accurate position.

It will be observed that the adjacent or opposed edges of the two die sections 1, 2 located adjacent to the radial gap are bevelled to bear against the end of the set screw 16 and that the hooks 14 of the clip 70 are formed to ride flat against said bevelled surfaces.

What I claim is:

1. A die comprising a plurality of thread-bearing sections separable one from another 75 and a spring clip peripherally binding them together said clip having an inturned hook at each end adapted to engage the opposed surfaces of two adjacent sections, substantially as described.

2. A die comprising a plurality of die-cutting sections separable one from another the adjacent edges of two sections being bevelled, and a spring clip peripherally binding the sections together, the ends of the clip having inturned hooks engaging said bevelled ends, substantially as described.

3. A thread-cutting die comprising a plurality of sections provided with internally threaded cutting edges, means for positioning and holding said sections in proper alignment comprising an annular clip having inwardly turned hooks and having an inwardly turned lip or flange adjacent to one side edge of the clip, substantially as described.

4. A thread-cutting die embracing in its construction a plurality of sections formed with interior threaded cutting-edges and a holding clip adapted to surround and hold 100 said dies in position, said holding clip being provided on one side edge with an inturned flange or lip whereby the die sections may be inserted from the opposite side without distorting or springing the clip beyond its 105 normal holding position, substantially as described.

5. A thread-cutting die comprising a plurality of sections each having an inwardly projecting thread-cutting edge, the internal 110 surface back of each cutting edge being formed on a center that is laterally offset to the diametrical line intersecting the middle point of the peripheral arc of the section, substantially as described.

6. A thread-cutting die embracing in its construction a plurality of sector shaped sections whose inner threaded surfaces extend on circles described about different centers that are laterally offset with relation to the 115 middle radius of each die section of the assembled die, substantially as described.

7. A thread-cutting die embracing in its construction a plurality of separable sections each of which is provided with inwardly projecting cutting edges in advance of internal surfaces formed on a circle described about a center that is asymmetrically offset with relation to the two radial edges of each die section in order to provide a sufficient 125 130 135

angle of clearance behind each cutting edge, substantially as described.

8. A thread-cutting die embracing in its construction a plurality of sector shaped die sections, a circumferential holding clip comprising a contractible split ring provided with an inturned flange presenting a side thrust surface at right angles to the axis of the die thereby affording a positive stop in contact with a side surface of each die section, substantially as described.

9. A thread cutting die comprising a plurality of sectors each of which is formed

with outside and inside circular surfaces, the inside circular face being described on a center that is asymmetrical to the outside circular surface whereby the sectors when assembled with their outer surfaces concentric will present interior cutting edges provided with an ample clearance behind each cutting edge.

In testimony that I claim the foregoing invention, I have hereunto set my hand this 17th day of April, 1919.

CARL J. PIHL.
